UNITED STATES PATENT OFFICE.

GEORGE H. HOLCOMBE, OF LAMBERTVILLE, NEW JERSEY.

BURIAL-VAULT.

1,267,225.

Specification of Letters Patent. Patented May 21, 1918.

Application filed December 1, 1917. Serial No. 204,906.

To all whom it may concern:

Be it known that I, GEORGE H. HOLCOMBE, a citizen of the United States, residing at Lambertville, in the county of Hunterdon and State of New Jersey, have invented 5 new and useful Improvements in Burial-Vaults, of which the following is a specification.

This invention relates to new and useful 10 improvements in burial vaults and the principal object of the invention is to provide a box having a groove in its marginal portion adapted to receive cement or like material and a cover having a flange adapted to enter 15 said groove for sealing the parts together.

Another object of the invention is to provide the cover with an outer flange for inclosing the marginal portion of the box and 20 adapted to receive and retain the cement forced from the groove by the inner flange or tongue.

Another object of the invention is to provide removable means on the box or body 25 for guiding the cover or top into place thereon.

Another object of the invention is to provide a device of this character which is simple and durable in construction, reliable and 30 efficient in operation and one which can be manufactured and placed upon the market at a minimum cost.

The invention also consists in certain other features of construction and in the 35 combination and arrangement of the several parts, to be hereinafter fully described, illustrated in the accompanying drawings and specifically pointed out in the appended claim.

40 In describing my invention in detail, reference will be had to the accompanying drawings wherein like characters denote like or corresponding parts throughout the several views, and in which:—

45 Figure 1 is an elevation partially in section and showing the guiding standard in place.

Fig. 2 is a cross sectional view.

As shown in these drawings 1 indicates 50 the box or receptacle which is preferably made of cement reinforced with steel rods as shown. The marginal portions of the box are provided with the grooves 2 and I prefer to form the outer walls of said 55 grooves by an outwardly projecting flange

3 so that the central lines of said grooves are in the same vertical plane as the outer walls of the receptacle. The top cover of the box is indicated at 4 and said cover is provided with a flange or tongue 5, and an 60 outer tongue or flange 6, said flange forming a groove 7. The parts are so proportioned that when the cover is put in position the inner flange 5 will engage with the grooves 2 and the outer flange 6 will inclose 65 the entire marginal part of the box. The top is provided with the staples 8 which are adapted to receive the usual straps for lowering the top into the grave. For guiding the top on to the box I provide the hinged 70 buckles 9 on the box which are adapted to receive the standards 10 which are so formed as to engage with the top and direct it into proper position on the box. As shown each standard is provided with a curved recess 75 11 for engaging with the curved part of the outer flange 3 and with an inclined end portion 12 engaging with the outer wall of the box so that the standards diverge outwardly 80 at their upper portions. The box or receptacle is lowered into position in the ordinary way and after the coffin is placed therein the top is lowered thereon, it being understood that the groove in the box is filled with cement or other suitable material. As the 85 flange 5 enters the groove 2 it will force some of the cement therefrom and said cement will fill up the space between the outer flanges of the top and box, thus making a 90 complete seal between the parts.

It is thought from the foregoing description that the advantages and novel features of my invention will be readily apparent.

I desire it to be understood that I may 95 make slight changes in the construction and in the combination and arrangement of the several parts, provided that such changes fall within the scope of the appended claim.

What I claim is:—

A vault comprising a box having a groove 100 in its upper edge, hinged buckles connected with the sides of the box, standards engaging said buckles, and having portions engaging with the box above and below said buckles, and a top guided into position on 105 the box by said standards, and having a tongue for engaging the groove.

In testimony whereof I affix my signature.

GEORGE H. HOLCOMBE.
